ICE MACHINE COMPANY, OF OMAHA, NEBRASKA, A CORPORATION OF NEBRASKA.

AUTOMATIC ELECTRIC SWITCH.

1,366,731.

Specification of Letters Patent. Patented Jan. 25, 1921.

Application filed March 31, 1919. Serial No. 286,559.

To all whom it may concern:

Be it known that I, HENRY A. HOESCHEN, a citizen of the United States, and a resident of Omaha, in the county of Douglas and 5 State of Nebraska, have invented certain new and useful Improvements in Automatic Electric Switches, of which the following is a specification.

My invention relates to electrically actuated and controlled switches, for use in 10 motor-circuits and the like, wherein it is desirable that the motor-circuit be opened and closed automatically to stop and start the motor, or to stop and start the operation of 15 other electrically operated devices, in accordance with conditions which are varied by the operation of the motor or other device controlled by the switch. It is the object of my invention to provide an efficient 20 and durable automatic switch, suitable for use in opening and closing circuits carrying heavy currents of moderate voltage, wherein the switch is actuated by a single solenoid, said solenoid energized by control-circuits, 25 and the control-circuits automatically opened and closed alternately with each other. A further object of my invention is to provide means for mechanically holding the main-switch brushes in engagement with 30 their contacts when the switch is in closed position, said holding means being yieldable and having a maximum power when the switch is closed, and said holding means having a continued tendency to move the 35 switch to closed position, but the tendency being variable non-uniformly. A further object of my invention is to provide a control-switch for establishing the control-circuits alternately, said control-switch being 40 actuated only at the conclusion of those movements of the solenoid-core necessary for effecting the opening and closing of the main-switch. More particular objects of my invention will appear hereinafter.

45 In the accompanying drawings Figure 1 is a front view of a switch mechanism embodying my invention, with typical circuits therefor represented diagrammatically, and the main-switch being shown in closed position, Fig. 2 is a detail front view of one of the closing-springs for the variable-tension device, Fig. 3 is a detail section of one of the main-switch contact-posts, on the line 3—3 of Fig. 4, Fig. 4 is a front view showing the

main-switch in open position, the solenoid 55 and adjacent parts being in vertical section, Fig. 5 is a detail horizontal section on the line 5—5 of Fig. 4, Fig. 6 is a vertical section through the main-switch, with parts of the control mechanism shown in side elevation, and Fig. 7 is a detail vertical section on the line 7—7 of Fig. 4.

In carrying out my invention according to the illustrated embodiment thereof, I provide a base or support 8 comprising a slab 65 of insulating material, such as slate or marble, disposed in a vertical position. On said base 8 the main-switch contact-posts 9, 10, 11 and 12 are arranged in pairs at opposite sides of and symmetrical to the center-line of the front face of the base-slab. Said contact-posts are secured to the base by screws 13 extending through the slab from back to front, as shown in Fig. 3, and are connected respectively with binding-posts 14, 15, 16 and 17, by suitable conductors indicated by dotted lines in Fig. 1. Feed-wires from a suitable generator G may be connected with the binding-posts 14 and 15, and a motor M, or the like, similarly 70 connected with the binding-posts 16 and 17. The pairs of contact-posts 9—11 and 10—12 are placed in electrical connection with each other by means of laminated brushes, each 75 comprising a series of normally flat plates 18, 19, 20 and 21, of resilient electrically conductive material, said plates being of graduated lengths, and the end-portions of the shorter plates being longitudinally kerfed or slotted, as shown in Fig. 5, to form 80 a series of independently yieldable fingers for engagement with the flat faces of the contact-posts. The longer plates 21 are 85 preferably provided at their ends with bent portions 22 forming dove-tail retaining- 90 sockets for removable blocks 23 of material such as carbon. The flat faces of the contact-posts are slightly inclined, being lower 95 at their inner edges, and the arrangement of the brush-plates is such that they assume 100 a downwardly bowed form when the switch is closed, the longer plates being bowed more than the shorter, so that as the brushes are moved vertically from open to closed position the blocks 23 are first to engage the 105 posts, and in the opening movement of the brushes the blocks 23 are last to leave the posts. By this means, any burning of the

brushes, due to the formation of arcs upon opening the switch, is confined to the renewable blocks 23.

The laminated brushes are carried by a vertically extending rod 24, which extends through central openings in the brush-plates, said rod being threaded and having thereon pairs of nuts 25 between which the plates are clamped, and suitable washers and bushings of insulating material 26 being provided and arranged as shown in Fig. 6, whereby the brushes are insulated from the rod. A metal washer, held beneath the upper clamp-nut 25 of the lower brush, has an integral finger 27 extending therefrom back toward the base 8, the end of said finger being notched and fitting slidably over a guide-rod 28 secured to the base, as shown in Fig. 6, said finger and guide-rod being employed to prevent rotation of the rod 24. Below the lower brush the rod 24 has a smooth or unthreaded portion which passes slidably through a guide-post 29, and beneath said post the terminal portion of the rod is threaded to receive the contoured wedge-body 30 of the variable-tension device, which will be fully described herein-after. On the threaded portion of the rod 24, above the upper brush, a sleeve 31 is screwed and retained fixedly by means of a set-screw 32 passing through the side thereof. A roller 33, mounted revolvably on a post 34 extending out from the base, bears against one side of the sleeve 31, forming an anti-friction guide therefor. At the opposite side of said sleeve the same carries a pair of laterally extending cam-plates 35 having contoured edges of which the upper portions 36 are parallel with the rod 24, and the lower portions 37 curve inwardly toward the rod. Between the upper portions of said cam-plates there is affixed a detent-bar 38 for retaining the main-switch in open position, said detent-bar being engageable by a latch-hook 39 when the rod 24 and its attached parts are in the raised position shown in Fig. 4. The latch-hook 39 extends in a nearly vertical position between the cam-plates 35, and is mounted pivotally upon a post 40 carried upon the base 8. An extended tail-portion on the latch-hook has a lower end-portion 41 turned outwardly from the sleeve 31, for a purpose which will presently appear. The latch-hook is impelled inwardly, or toward the detent-bar 38, by means of a spring 42 connected therewith through the medium of the control-switch arm 43. Said arm is secured to the latch-hook and moves therewith about the pivot-post 40, the arm extending in a nearly horizontal position between the rod 24 and the face of the base-slab 8, and carrying at its end a bar of insulating material 44. The lower end of the spring 42 is attached to a metal contact-strip 45 secured on the rear

side of the bar 44, and the upper end of the spring is attached to a hook-plate 46 secured on the base, as shown. The contact-strip 45 is adapted for engagement with a pair of slotted resilient contact-fingers 47 and 48 which are mounted on the base and connected, respectively, with binding-posts 49 and 50.

Above the sleeve 31 the rod 24 has a smooth or unthreaded portion on which the tubular solenoid-core 51 is slidable. Said core is flattened at one side near the lower end thereof, and a stop-post 52 is arranged on the base 8 so as to extend alongside said flattened part, to thereby prevent rotation of the core, and also to limit downward movement of the core by engaging the shoulder formed at the upper end of the flattened portion. At the side of the core opposite the flattened portion there is a lug 53 to which is pivotally connected the upper end of a U-bar 54 which extends downward around the front and rear sides of the core and of the sleeve 31, the lower horizontal part of the bar resting against the contoured edges of the cam-plates 35. The upper end of the core 51 fits slidably within the lower part of a solenoid comprising a suitably insulated coil 55 wound upon a spool formed by a sleeve 56 and upper and lower end-plates 57 and 58, said end-plates being secured to the base-slab 8, and the terminals of the coil being attached to binding-posts 59 and 60. The upper end-plate has an integral tubular portion 61 extending down inside the sleeve 56. The rod 24 has an upper terminal portion of reduced diameter, which passes slidably through the part 61, the rod projecting beyond the upper end-plate of the spool and being engageable with a cushioning facing-disk 62 carried by a bracket 63 mounted on the base 8 above the solenoid, the structure forming a stop for limiting upward movement of the rod and the core, under the impetus given the latter when the solenoid is energized. Within the sleeve 56 of the solenoid-spool, above the end of the core 51, a collar 64 is screwed on the rod 24, as shown in Fig. 4, said collar forming an abutment against which the core may strike to lift the rod.

Referring now to the variable-tension device at the lower end of the switch-rod 24, the guide-post 29 has on opposite sides thereof pairs of lugs 65 between which are pivoted the upper ends of levers 66. Said levers carry at their lower ends rollers 67 which engage opposite sides of the contoured wedge-block 30, being pressed yielding against the same by means of a plurality of springs 68 of the form shown in detail in Fig. 2, the inwardly turned ends of said springs being inserted in holes formed in the outer sides of the levers 66. Said springs, being symmetrically formed at 130

their opposite sides, press in equally upon the levers, so that the pressure of the rollers upon the wedge-body is equalized at the two sides of the body, and thus will have no tendency to move the same laterally. It will be apparent that the inward pressure of the rollers upon the inclined surfaces of the wedge-body will have a tendency to push the wedge-body and rod 24 downwardly when the rollers are in engagement with an upwardly tapering portion of the body, and that the amount of pull or tension thus exerted upon the rod will vary according to the taper of the wedge-body at the points engaged by the rollers. Thus, by suitably contouring the wedge-body, any desired tension upon the switch-rod may be exerted at any portion of its travel, and the movement of the rod assisted more or less as may best suit the operation. In the structure shown, the lower portion of the body 30 is flared so as to offer increased resistance to upward movement of the rod when the latter approaches its upper limit of movement, and to have a corresponding tendency to promptly initiate downward movement of the rod when the same is released. The intermediate portion of the body 30 has a gradual taper, so that the tension upon the rod is moderate during the intermediate portion of its travel. Near the upper end of the body 30 the inward taper thereof is abruptly increased, and the same is then slightly flared, the least width of the body being at the point reached by the rollers when the rod is at the lower limit of its movement. Obviously, in the downward movement of the rod, the tension will be augmented as the rollers engage the abruptly tapered portion of the body, and this effect is utilized for bringing the switch-brushes into firm engagement with the contact-posts, and bending the brush-plates. Contrariwise, the spring of the brushes assists in overcoming the resistance of the wedge-body to upward movement of the rod at the beginning of the switch-opening movement, while the slightly tapered intermediate portion of the wedge-body causes but slight resistance to the intermediate part of the upward travel of the rod.

To illustrate the operation of the switch mechanism, it will be assumed that the motor M is used to drive a compressor for a refrigerant; that it is desired to start the operation of the compressor when the temperature of a refrigerated chamber reaches a determined maximum, and to stop the operation of the motor and compressor when the temperature of the chamber has been reduced to the desired degree. A thermostat T, placed in the refrigerator-chamber, has stationary contacts 69 and 70 and an intermediate movable arm 71 which is impelled toward the contact 69 by a rise of

temperature, and toward the contact 70 by a decrease of temperature. The contacts 69 and 70 are electrically connected, through the binding-posts 49 and 50, with the control-switch contact-fingers 47 and 48, respectively. The thermostat-arm 71 is connected with a source of electrical energy, as to one side of the supply-circuit for the motor, and the other side of said source is connected with one terminal of the solenoid coil, as by a conductor 72 connecting the binding-posts 14 and 60. The other terminal of the solenoid coil is connected by a conductor 73 with the hook-plate 46, the latter being connected by the spring 42 with the contact-strip 45 of the control-switch. The main-switch being in the closed position shown in Fig. 1, the latch-hook 39 is held out by the detent-bar 38, so that the arm 43 is in a lowered position at which the contact-strip 45 engages the finger 48. If now the thermostat-arm 71 moves into engagement with the contact 70, a circuit through the solenoid is closed, the solenoid is energized, and the core 51 is thereby pulled upwardly. The upper end of the core 51, engaging the collar 64, lifts the switch-rod 24. Said upward movement of the rod is resisted by the weight of the parts carried thereon, and also by the downward thrust of the spring-pressed rollers 67 on the wedge-block 30. The upward movement is assisted initially, however, by the straightening of the resilient brush-plates of the main-switch, the reaction of said plates being effective simultaneously with the movement of the rollers 67 over the abruptly inclined portions and onto the moderately inclined or tapered portions of the wedge-block 30. At the conclusion of the upward movement of the switch-rod, the detent-bar 38 passes the ledge or offset of the latch-hook, so that the latter may drop in beneath the detent-bar, and the spring 42 raises the arm 43 to so move the latch-hook, and to simultaneously open the solenoid control-circuit by moving the strip 45 out of engagement with the contact 48 and into engagement with the contact 47. Upon de-energization of the solenoid, the core 51 drops to the lower position thereof shown in Fig. 4, but the main-switch is held open by the latch-hook. If now, the thermostat arm 71 be moved to engage the contact 69, the second control-circuit is completed and the solenoid again energized to lift the core 51. As the core commences to move upward the lower horizontal portion of the U-bar 54 passes under the outwardly turned tail-piece 41 of the latch-hook, and as the movement continues the inclined edges 37 of the cam-plates 35 cause the U-bar and latch-hook to swing out laterally from the rod 24, as shown by dotted lines in Fig. 4, thereby disengaging the hook from the de-

tent-bar 38 and releasing the rod 24 for downward movement to the switch-closing position. The lateral movement of the latch-hook moves the control-switch arm from the 5 raised position back to the lowered position thereof shown in Fig. 1, thus opening the second control-circuit at the contact-finger 47 and strip 45, but reestablishing the first control-circuit except at the thermostat contacts.

It will be seen that the work of the solenoid in releasing the latch-hook, to enable closing of the switch, may be less than that necessary in opening the switch, but that 15 the energization of the solenoid will be automatically proportioned to the required energy-output therefrom. Thus, in both the switch-opening and switch-closing operations, the completion of the effective movement 20 of the solenoid-core is immediately followed by movement of the latch-hook and control-switch to open the energizing control-circuit, and in neither instance can the control-circuit be opened to cause de- 25 energization of the solenoid until actuation of the main-switch parts has been completed or so initiated as to be automatically completed.

The variable-tension device applied to the 30 lower end of the switch-rod 24, as described, enables resistance to upward movement of the switch-rod to be so apportioned in the several parts of the stroke as to best suit the operating conditions, giving due considera- 35 tion to the effective pull of the solenoid-core at different parts of its stroke, and to the resistance of the core-movement offered by the other parts of the mechanism. Thus said tension device contributes materially to 40 smoothness and certainty of operation of the mechanism, with a solenoid of minimum size and cost of construction.

Now, having described my invention, what 45 I claim and desire to secure by Letters Patent is:

1. In an automatic electric switch, a switch member movable reciprocatingly between a circuit-opening and a circuit-closing position, variable-tension means connected 50 with said member and tending to move the same to one position, electromagnetic actuating means for moving said member to the other position, a latch engageable with the member for retaining the same in the latter 55 position, and means movable by said actuating means for disengaging the latch to release the switch-member.

2. In an electric switch of the class de- 60 scribed, a rod mounted to reciprocate longitudinally, resilient brushes carried thereby, contacts engageable by said brushes, variable-tension means connected with said rod and adapted to hold said brushes in stressed form against said contacts, electromagnetic 65 actuating means for moving the rod to dis-

engage the brushes from the contacts, means for holding the rod in the position to which it is moved by said actuating means, and means for releasing said holding means.

3. In an electric switch of the class de- 70 scribed, a reciprocating main-switch member, yieldable tensioning means connected with said member and tending to move the same in one direction, electro-magnetic actuating means for moving said member in the 75 other direction, control-circuits for said electro-magnetic actuating means, a control-switch for said circuits, a latch connected with said control-switch and movable therewith, said latch being engageable with the 80 main-switch member for preventing movement thereof by the tensioning means, and a releasing member controlled by the electro-magnetic actuating means and engageable with the latch when the latter is engaged 85 with the main-switch member, said releasing member adapted to move the latch to a release position and to move the control-switch to reverse the control-circuit connections.

4. In an electric switch of the class de- 90 scribed, a solenoid, two control-circuits therefor, a control-switch arranged to establish said circuits alternatively, a core 95 movable in one direction by energization of said solenoid and biased to move in the opposite direction upon deenergization of the solenoid, a main-switch member actuatable by movement of said core in the direction first named, tensioning means opposing movement of said main-switch member by 100 said core, a latch for holding said switch member in the position to which it is movable by said core, and means actuated by the core for moving said latch to a release position, said latch and the control-switch being 105 connected for reciprocal actuation.

5. In an electric switch of the class de- 110 scribed, a main switch having fixed contacts, flexible brushes engageable with said contacts, a slidably mounted rod carrying said 115 brushes, electromagnetic means for actuating said rod to move the brushes away from the contacts, and variable-tension means connected with the rod for actuating the same to move the brushes into engagement with the fixed contacts and to flex the same thereagainst, said variable-tension means arranged to exert an increased force upon the rod during the brush-flexing portion of its travel.

6. In an electric switch of the class de- 120 scribed, a reciprocating main-switch member, means biasing said member to movement in one direction, electromagnetic actuating means for moving said member in the other 125 direction, control-circuits for said electro-magnetic actuating means, a control-switch arranged to establish said circuits alternatively, and a holding element connected to and movable with said control-switch, said 130

holding element being engageable with the reciprocating main-switch member when the control-switch is in position to establish one control-circuit, and said holding element arranged to release the main-switch member simultaneously with movement of the control-switch to open the last-named control-circuit and establish the other.

7. In an electric switch of the class described, a reciprocating switch-member, resilient brushes carried thereby, contacts engageable by said brushes, means for moving the switch-member to a position at which the brushes are held away from the contacts,

means for holding the switch-member in said position, means for moving said holding means to release the switch-member, and a variable-tension device connected with the switch-member and tending to move the same to a position at which the brushes are engaged with the contacts and flexed thereagainst said variable-tension device comprising a wedge-body contoured symmetrically at its opposite sides, a pair of rollers engaging the contoured sides of the body, and means for pressing said rollers against said body. 15
